A reversible beverage container, as shown and described.

DESCRIPTION

FIG. 1 is a perspective view of a reversible beverage container;

FIG. 2 is a sectional view of the reversible beverage container of FIG. 1;

FIG. 3 is a front view of the reversible beverage container of FIG. 1;

FIG. 4 is a top view of the reversible beverage container of FIG. 1; and,

FIG. 5 is a bottom view of the reversible beverage container of FIG. 1.

The left, right and back views of the reversible beverage container according to the present invention are duplicative of the front view, and thus are omitted from the Specification. The broken lines illustrate portions of the design that form no part of the claim.
